TYPE HOLDER
William B. Miles, Bedford, Va.
Filed Mar. 23, 1959, Ser. No. 801,310
4 Claims. (Cl. 101—394)

This invention relates to the art of printing and is more particularly directed to a holder for type.

In my prior patents, 2,821,916 entitled "Printing Machines," and 2,775,196 entitled "Rotary Printing Machine with Flat Printing Plate," I disclosed and claimed printing machines particularly designed for use in the imprinting of checks with the depositor's name, address, and such other useful information as may be desired. These machines were necessarily provided with means for securing type in lines or sticks in proper printing position therein and the means there conceived of was a block suitably recessed to receive inverted T-shaped or footed type, inserted in position element by element. Obviously, insertion of type in this manner is tedious and requires direct handling which may cause the fingers to be stained with ink.

The present invention has to do with an improved form of type holder for one or more of these machines, such holder being especially designed with a view to facilitating removal of type, preferably in the form of sticks previously prepared by ways known in the art, when one imprinting order has been completed and the replacement therein of fresh type for the imprinting of a new order. While the holder of the invention has particular utility in association with one or more of my check imprinting machines, its usefulness is not necessarily limited thereto and the novel principles and features embodied therein may be employed with advantage in other machines and in the printing of materials other than checks.

It is one of the objects of the present invention to provide a self-contained type holder having an improved arrangement for releasably retaining type therein.

Another object of the invention is to provide a holder of the type described including means for clamping the type in proper printing position between two opposed members and for automatically separating these members when the clamping force is released to facilitate removal and replacement of the type.

A further object is the provision of a holder of the type described wherein the clamping means is self-aligning with respect to the type.

A still further object of the invention is a holder of the type described which is adapted to retain two spaced apart groups of type, a single clamping means serving to retain both groups in proper printing position.

Other objects and advantages will be brought to mind by the following detailed description when read in conjunction with the accompanying drawings, in which:

FIG. 1 is a top plan view of the holder of the invention showing the clamping cam in operative position;

FIG. 2 is a view similar to FIG. 1 but with the type removed and with the clamping cam shown in inoperative position;

FIG. 3 is a view in section taken generally along line A—A of FIG. 1;

FIG. 4 is a view in section taken generally along line B—B of FIG. 3; and,

FIG. 5 is a view of the rear of the holder.

In the drawings, the numeral 10 generally designates a solid, three-dimensional block or base member, ordinarily of rectangular plan configuration and cast or otherwise formed metal, which block forms the basic component of the holder of the invention, carrying or supporting all of the remaining elements. As can be best seen in FIGS. 2 and 4, along each side of the top face of

2

block 10, parallel to the major or greatest axis thereof, is an upstanding rib or flange 12 which forms one retaining member for the type. Immediately adjacent each of the flanges 12, the top face of the block is formed with a plane surface 14, preferably of elongated rectangular shape, which is adapted to receive and support type T, indicating the depositor's name, address, account number or such other information as may be desired. It is desirable for the purposes of the invention that the type be assembled in the form of sticks in any of the customary ways of the art. Between the planar surfaces 14, the top face of the block is recessed, as at 16, except for a central rib or cross-bar 18, there being, consequently, two oppositely facing recesses 16, one at each end of the block, separated by the cross-bar 18. Recesses 16 are of a shape in cross-section of a shallow U and in plan of a deeper U. From this description it will be understood that the top face of the block, in effect, is in the form of an H, wherein the legs of the H are the plane surfaces 14, the transverse connection of the H is the cross-bar 18 and the open portions are the recesses 16, with the flanges 12 extending along the extreme side edges of the block and projecting at right angles to its face.

Mounted for pivotal movement on the surface of cross-bar 18 is a clamping cam 20 which is held in place by means of a bolt 22 passing through an aperture 23 provided in cross-bar 18, the bolt being threaded at its lower end for the reception of a retaining nut 25. In the preferred embodiment of the holder as illustrated, the cam is of the double-acting type, being effective to exert clamping force in both directions laterally thereof. To this end, cam 20 is generally in the form of a thin rectangular or square plate-like element having two opposite corners cut away as at 24 to provide "flats" thereon, the remaining two opposite corners of the cam plate being extended outwardly in the form of narrow arms or levers 26. To facilitate manufacture of the cam, the portions thereof constituting the arms and "flats" may be formed separately and attached, as by welding, to the rectangular center portion, but this is a refinement and the cam can obviously be formed in other ways. In actuating cam 20, levers 26 are grasped or engaged by the fingers of the operator and it is advantageous to suitably shape and/or curve levers 26 in the manner shown in the drawings to facilitate their manipulation. The presence of recesses 16 also makes the levers 26 more accessible.

Disposed on each of the plane surfaces 14 in spaced relationship to the flanges 12 and directly adjacent the terminations of cross-bar 18 is a clamping bar 30, of a length generally the same as that of surface 14. There is secured to the approximate midpoint of each bar a pin 32, projecting downwardly from the undersurface of the bar and passing through an aperture 34 provided in the block for that purpose. Each of the apertures 34 is enlarged or elongated in a direction transverse to the major axis of the block so that each pin 32 is capable both of pivotal and limited lateral movement with respect to its corresponding aperture. Adjacent the lower end of each pin is an enlargement or collar 36 having a diameter in excess of the largest dimension of aperture 34, and below the collars 36, the pins are connected together by a spring 38 in tension. It will be seen that clamping bars 30 are maintained in position on the planar surfaces 14 by pins 32, collars 36 preventing the removal of the pins from apertures 34, and that the bars are urged towards one another by spring 38 to the extent permitted by apertures 34.

As can be seen in FIGS. 2 and 4, each of the clamping bars 30 is provided in its mid-portion, comprising about $\frac{1}{3}$ of its length, with an elongated kerf or slot 40 ex-

tending parallel to the longitudinal axis of the bar and spaced considerably closer to the inner side than to the outer side of the bar. Kerf 49 may be formed by cutting the bar from one end thereof, as at 42, towards the other end, but terminating the cut before reaching the other end, and then enlarging the cut at the mid-portion to form the slot 49. The presence of kerf 49 permits the adjacent strip-like portion 41 of the bar to yield under pressure, acting much as a leaf spring to permit repeated yielding without breaking. The bar should be constructed from a material that is relatively free of fatigue, such as spring steel.

In FIG. 2, the clamping cam 20 is shown in inoperative position with the arms 26 closely adjacent opposite ends of the two clamping bars 30. When cam 20 is in such position, clamping bars 30 are free to move under the influence of spring 38 towards one another as far as permitted by apertures 34 or until they contact the side walls of clamping cam 20. The transverse or minimum dimension of cam 20 is ordinarily so selected that the side walls thereof will just contact the inner sides of the clamping bars when the latter are in or very near their very maximum inner position. With the cam in inoperative position, the type supporting surfaces 14 are exposed or opened to the fullest degree possible; consequently, sticks of type may be placed thereon, or removed therefrom, with a maximum of ease and minimum of resistance. The type having been put in place, the cam operating arms 26 are grasped manually and manipulated to pivot the cam until the flattened surfaces 24 contact and seat against the inner side walls of the clamping bars 30.

The diagonal dimension of cam 20, i.e. the distance between the "flats" 24, is somewhat greater than the minimum transverse dimension between its side walls in order that the rotation of the cam forces the clamping bars apart in the direction of their corresponding flanges 12, such movement being, of course, permitted by the transversely elongated slots 34. This diagonal dimension is selected such that it slightly exceeds the dimension separating the clamping bars when the latter are urged as far as possible against type sticks T in the direction of flanges 12 so that the yieldable mid-portions of the clamping bars are placed under compression when cam 20 is in operative position with the flats seating against the sidewalls of the clamping bars. In this way, the type sticks are maintained in printing position under spring pressure which also serves to hold the cam in operative position and prevent inadvertent movement of the cam therefrom.

As has already been brought out, the clamping bars are mounted for both pivotal and limited sliding movement with respect to surfaces 14. The bars, therefore, adjust themselves more or less automatically to type sticks which vary slightly in thickness or in the parallelism of their side walls and are, in effect, self-aligning relative to the type.

As can be best seen in FIGS. 3-5, it has been found advantageous to provide the bottom face of the block 10 with a transverse recess 44 to accommodate the lower portion of pins 32 and bolt 22 and prevent their projecting below the bottom face of the block as well as with feet 46 which maintain the undersurface of the block in slightly spaced relationship to any supporting surface. These details, however, are unnecessary to the actual functioning of the holder and may be omitted or altered to fit a given set of circumstances.

While the invention has been illustrated as capable of receiving two sticks of type on one supporting surface 14 and one stick of type on the other of such surfaces, it will be appreciated that this is for purposes of illustration only and that the dimensions of the block may be modified to accommodate any desired number of sticks of type. Moreover, where the available space is in excess of the actual number of sticks required for a given pur-

pose, it will be borne in mind that fillers or spacers may be employed to occupy this excess area. Other modifications in design and detail of the construction will naturally occur to one skilled in the art. Accordingly, it is not intended that the invention should be limited to the exact details of the illustrative embodiments, but only as is required by the appended claims.

Having thus described my invention, that which is claimed is:

10. A type holder comprising a base member including an elongated upstanding rib and a planar surface adjacent said rib, which surface is adapted to support type; a cam member adjacent said surface in opposed relation to said rib and mounted for pivotal movement about an axis extending at right angles to said surface; an elongated bar retained on said surface adjacent said cam and in spaced parallel relation to said rib, said bar being adapted for limited movement towards and away from said rib, and spring means connected to said bar for biasing said bar toward said cam, said cam being operative upon pivotal movement to act upon said bar and move the same laterally toward said rib against the force of said biasing means to thereby clamp type on said surface between said bar and said rib and said spring means being operative to move said bar away from said rib to release the type when said cam is rendered inoperative, said bar being provided with a long, thin slot extending parallel to the bar axis adjacent the side of the bar contacted by said cam and terminating at points spaced from the bar ends, said slot passing through said bar along a plane parallel to the pivot axis of the cam and separating a thin strip of the bar from the remainder thereof except adjacent the bar ends, the locus of contact of the cam with the bar being within the limits of said slot whereby said thin strip is contacted by said cam and is adapted to yield under the force thereof to exert a biasing force on the remainder of the bar in the direction of said elongated rib.
20. A type holder as in claim 1 wherein the planar surface of said base member is formed with an elongated aperture having its major axis at right angles to said upstanding rib and extending from said surface perpendicularly into said block, and including a pin loosely fitting within said aperture and retained against axial withdrawal therefrom, one end of said pin being connected to said elongated bar and said spring means is connected to said pin to bias said pin and said elongated bar away from said upstanding rib.
30. A type holder comprising a base member including a planar surface having an elongated slot extending parallel to the axis of said base member, an elongated upstanding rib and a cam member adjacent said surface in opposed relation to said rib and mounted for pivotal movement about an axis extending at right angles to said surface; an elongated bar retained on said surface adjacent said cam and in spaced parallel relation to said rib, said bar being adapted for limited movement towards and away from said rib, and spring means connected to said bar for biasing said bar toward said cam, said cam being operative upon pivotal movement to act upon said bar and move the same laterally toward said rib against the force of said biasing means to thereby clamp type on said surface between said bar and said rib and said spring means being operative to move said bar away from said rib to release the type when said cam is rendered inoperative, said bar being provided with a long, thin slot extending parallel to the bar axis adjacent the side of the bar contacted by said cam and terminating at points spaced from the bar ends, said slot passing through said bar along a plane parallel to the pivot axis of the cam and separating a thin strip of the bar from the remainder thereof except adjacent the bar ends, the locus of contact of the cam with the bar being within the limits of said slot whereby said thin strip is contacted by said cam and is adapted to yield under the force thereof to exert a biasing force on the remainder of the bar in the direction of said elongated rib.
40. A type holder as in claim 1 wherein the planar surface of said base member is formed with an elongated aperture having its major axis at right angles to said upstanding rib and extending from said surface perpendicularly into said block, and including a pin loosely fitting within said aperture and retained against axial withdrawal therefrom, one end of said pin being connected to said elongated bar and said spring means is connected to said pin to bias said pin and said elongated bar away from said upstanding rib.
50. A type holder comprising a base member including an elongated upstanding rib and a planar surface adjacent said rib for supporting type; an elongated rigid clamping bar disposed on said surface in spaced relationship to said rib and cooperating with said rib to retain type contiguously there between, said bar being adapted for movement towards and away from said rib; an elongated resilient strip extending generally parallel to the axis of said bar along the side thereof remote from said rib, said strip contacting said bar adjacent its ends and having an intermediate portion spaced from said bar, whereby said intermediate portion may be deformed towards said bar to flex the strip, and a cam member mounted on said base member on the side of said strip remote from said bar for pivotal movement about an axis parallel to the plane of said strip and adapted to contact the intermediate portion of the strip, said cam being operative to move the strip and bar towards said rib to the extent permitted by the type and then to deform the intermediate portion towards the bar whereby the resilient force of the strip is exerted against the bar to clamp the type in place.
60. A type holder as in claim 3 wherein said cam member is of the over-center type and is provided with a flattened surface adapted to seat against said intermediate portion when in over-center position, said intermediate portion being deformed by the movement of the cam to
70. A type holder as in claim 3 wherein said cam member is of the over-center type and is provided with a flattened surface adapted to seat against said intermediate portion when in over-center position, said intermediate portion being deformed by the movement of the cam to
75. A type holder as in claim 3 wherein said cam member is of the over-center type and is provided with a flattened surface adapted to seat against said intermediate portion when in over-center position, said intermediate portion being deformed by the movement of the cam to

over-center position and remaining deformed when said flattened surface is seated thereagainst.
